MOTORCYCLE LUGGAGE RACK

Aleksis Lahti, Ann Arbor, Mich., assignor to American Safety Equipment Corporation of Michigan, Southfield, Mich.

Filed Feb. 20, 1967, Ser. No. 5,883

Term of patent 14 years

(Cl. D90—3)

FIG. 1

FIG. 2

FIG. 3

FIG. 1 is a top plan view of a motorcycle luggage rack, showing my new design.

FIG. 2 is a left side elevational view thereof, the right side being an identical mirror image.

FIG. 3 is a front elevational view thereof.

FIG. 4 is a perspective view thereof.

I claim:

The ornamental design for a motorcycle luggage rack, as shown and described.
